UNITED STATES PATENT OFFICE

SAMUEL M. ANDERSON, OF HYDE PARK, MASSACHUSETTS, ASSIGNOR TO B. F. STURTEVANT COMPANY, OF HYDE PARK, MASSACHUSETTS, A CORPORATION OF MASSACHUSETTS

AIR CONDITIONING APPARATUS

Application filed June 11, 1929. Serial No. 370,069.

The present invention relates to air conditioning apparatus such as heaters, coolers, humidifiers, and the like.

The object of the present invention is to re-
5 organize and improve air conditioning apparatus particularly with a view to flexibility of construction and assembly, whereby stock units may be assembled and combined in any desired number.

10 With this object in view, the present invention consists of the air conditioning apparatus hereinafter described and particularly defined in the claims.

15 The drawing is an elevation partly in section of air conditioning apparatus embodying the features of the present invention.

20 The invention comprises a plurality of units which include one or more humidifiers or washers and one or more temperature controlling units such as heaters or coolers. As shown in the drawing, the invention is embodied in an apparatus having a single humidifier and a single heater. The humidifier or washer is indicated at 2 and is of 25 the general type disclosed in my co-pending application Serial No. 323,951, filed December 5, 1928.

Briefly, this type of washer comprises a plurality of rows of nozzles 4 each including 30 a number of air tubes 6 associated with water tubes 8. The air and water tubes have opposed openings whereby the suction produced by the passage of air across the openings of the water tubes acts to disperse the water in 35 a fine spray through the chamber.

The washer is provided with an inlet filter 10 and an outlet filter 12. These filters are primarily for the purpose of eliminating dust and entrained particles of water. These filters may be of any suitable form but are preferably of metal wool presenting a large number of interstices through which the air may 40 pass in tortuous paths. On the inlet side of the washer is a propeller fan 14 driven by a 45 motor 16.

Following the washer is an air heater indicated generally at 18. Inasmuch as it is desirable to manufacture certain standard forms of units for assembly in any desired 50 combination, each unit is supplied with its

own fan. Thus, for the heater there is provided a fan 20 of sufficient size to overcome the resistance of the heater. The fan is driven by a motor 22. As shown in the drawing, the fan 14 is of sufficient size to overcome 55 the resistance of the washer and the filters while the fan 20 is large enough to overcome the resistance of the heater. By the use of individual fans, each unit may be constructed and designed to operate with a fan of a certain size and the assembly need not be altered to permit the addition of other units as would be necessary if fans of different sizes were employed to overcome the resistances of a variable number of units.

60 The operation of propeller fans in series has proven difficult because of the fact that each fan produces a spin in the fluid. This spin is a necessary incident to work done by the fan. In fact, the amount of spin increases as the power output of the fan increases. The presence of a spin component in the inlet of a fan, however, introduces difficulties in the operation. Thus, when two 65 fans are mounted for series operation, the 70 spinning air from the first fan necessarily passes to the inlet of the second fan. If both fans rotate in the same direction, the capacity of the second fan for overcoming resistance 75 is materially reduced, whereas if they rotate in opposite directions, the tendency is for the second fan to take an excessive proportion of the load.

According to the present invention, the 80 filters 10 and 12 not only serve the purpose of removing dust and entrained water from the air, but also damp out the spin component of velocity so that the air flows to the second fan in substantially a straight axial stream. Inasmuch as the filters are of some thickness, 85 they effectively prevent the transverse flow of air to which the spin component gives rise. Thus, the resistance to transverse flow is sufficiently high to remove the spin without, however, interposing an excessive resistance in 90 the path of general axial flow of the fluid.

95 Although the preferred form of nozzle is of the type described in the co-pending application above referred to, the present invention is not limited to such specific nozzle but 100

may employ any suitable water spraying or atomizing means.

The invention having been thus described, what is claimed is:

- 5 1. Air conditioning apparatus comprising a plurality of air conditioning units including a humidifier unit, a propeller fan for each unit, the humidifier unit being disposed between successive fans, and means located be-
- 10 tween the fans for damping the spin velocity introduced into the air stream of the first fan.
- 15 2. Air conditioning apparatus comprising a plurality of air conditioning units including a humidifier unit, a propeller fan for each unit, the humidifier unit being disposed between successive fans and including a filter for removing dust and entrained water particles and having a high resistance to trans-
- 20 verse flow of air to remove the spin from the air stream introduced by one of the fans.
- 25 3. Air conditioning apparatus comprising an air washer unit, a temperature controlling unit, a fan for each unit, the washer unit being disposed between the fans and including a filter for removing dust and entrained water and for damping the spin velocity introduced into the air stream by the first fan.

In testimony whereof I have signed my
30 name to this specification.
